THIOPHOSPHORIC ACID ESTERS AND THEIR PRODUCTION

Walter Lorenz, Wuppertal-Elberfeld, and Gerhard Schrader, Wuppertal-Cronenberg, Germany, assignors to Farbenfabriken Bayer Aktiengesellschaft, Leverkusen, Germany, a corporation of Germany

No Drawing. Filed Mar. 12, 1957, Ser. No. 645,403

Claims priority, application Germany Nov. 22, 1955

12 Claims. (Cl. 260—461)

This invention relates to and has as its objects new and useful thiophosphoric acid esters and their production. More specifically this invention is concerned with a class of thio- and dithiophosphoric acid esters of the general formula

in which R, R¹ and R² stand for alkyl, especially lower alkyl radicals, A stands for a lower branched alkylene chain, X stands for either oxygen or sulfur and Y stands for S, SO or SO₂.

Thio- and dithiophosphoric acid esters are known as effective insecticides and especially such compounds of the above indicated type in which the alkylene chain is not branched have become of special importance recently. Considerable work has been done in this field to find more effective and less toxic thiophosphoric acid esters of the above type.

In accordance with the present invention there has been found a new class of thio- and dithiophosphoric acid esters of the above general formula, particularly such thio- and dithiophosphoric acid esters of the formula

in which R, R¹, R², X and Y have the same significance as described above. Thus, this invention relates to S-[alkylmercapto-(sulfoxyl and sulfonyl)-(branched-ethyl)]-O,O-dialkyl-thiol-(and thiono-thiol)-phosphoric acid esters. Without restricting this invention in any way, there may be mentioned as example the compounds of the following formulae:

The corresponding sulfoxyl and sulfonyl branched alkylene compounds as well as the corresponding thiono-thiophosphoric acid esters are, of course, also within the scope of the present invention.

The preparation of these compounds may be effected by various methods. Thus, a general method for obtaining these compounds consists in reacting a salt of an appropriate O,O-dialkyl-thiol-(or thiono-thiol)-phosphoric acid with the desired alkyl-mercapto- (or sulfoxyl- or sulfonyl-) alkyl halide as shown by the following equation:

in these formulae R, R¹, R², X and Y have the same significance as shown above. Hal stands for halogen and Me for a salt forming radical. This method is known e.g. from German Patent 830,509 (alkylmercapto-alkyl-halides as reaction compounds).

Other known methods, however, may also successfully be used to prepare the inventive compounds. Thus, dialkylphosphites may be reacted with the appropriate alkyl thiocyanides or dialkylphosphoric or thionophosphoric acid-halides may be reacted with alkyl-mercapto-alkyl mercaptans. Also S-(β -haloalkyl)-O,O-dialkyl-thiol-(or thiono-thiol)-phosphoric acid esters may be reacted with suitable mercaptans, thus yielding the desired alkylmercapto-branched alkylesters. If sulfonylalkylesters are desired it is also possible to add appropriate vinylalkylsulfones to O,O-dialkyl-thiol-(or thiono-thiol)-phosphoric acids or to react alkylsulfonylalkylsulfohalides with O,O-dialkyl-phosphoric acids. Finally, sulfoxyl and sulfonylalkylesters may be prepared by oxidizing the corresponding alkylmercaptoalkylesters. This last method is described e.g. in U.S. application Ser. No. 544,832 (sulfoxides) and Ser. No. 526,557 (sulfones). All the above mentioned methods of preparations refer to unbranched alkyl compounds. The inventive new esters may be prepared according to all these methods and by using exactly the amount of branched alkyl-reactant instead of the corresponding molecular-amount of unbranched alkyl-compound.

The new esters are generally valuable insecticides of high activity and low toxicity. They may be used to kill flies, mosquitos, aphids, mites and the like. The applications may be effected in the usual way i.e. as other phosphorous insecticides may be used. Thus, for example, concentrations from 0.00001% to about 1% are usually sufficient enough to guarantee effectiveness. The new esters may furthermore be used in combination with solid and liquid carriers such as talc, chalk, bentonite, clay or water (if necessary with suitable commercial emulsifiers) alcohols, lower aliphatic hydrocarbons, aromatic hydrocarbons etc. Most of the new compounds exhibit also strong systemic activity. The compounds, thus, may be brought in contact in any way with insects to be killed or plants to be protected. As a special example for the utility of some of the in-

ventive compounds there are given below the activities of some compounds. The tests are carried out as follows:

Spray solutions were prepared by dissolving the active ingredient in the same amount of dimethylformamide. After having added about 10% this weight of a commercial emulsifier e.g. a benzyl hydroxydiphenyl polyglycol ether having about 15 glycol residues in its chain or a sulfonated glycol ester of a long chain fatty acid, the organic solution is diluted with water to the concentrations indicated below. For the determination of toxicity rats were fed with baits containing the active ingredient indicated below. The figures under toxicity, show from right to left the quantity of animals: tested/with symptoms/killed.

Toxicity.....10 mg./kg. 1/5/5
(Rats orally).....25 mg./kg. 5/5/5 (LD 95)

		Percent	Percent
insecticidal values.....	flies.....	0.01	100
	grain weevil.....	0.1	100
	black bean aphids.....	0.001	100
	Colorado beetles.....	0.1	80
	systemic action on black bean aphids.....	0.1	100

Toxicity.....10 mg./kg. 3/5/5
(Rats orally).....25 mg./kg. 5/5/5 (LD 95)

		Percent	Percent
insecticidal values.....	spider mites.....	0.01	100
	flies.....	0.1	100
	black bean aphids.....	0.001	100
	mosquito larvae.....	0.001	70
	systemic action on black bean aphids.....	0.1	100

Toxicity.....10 mg./kg. 3/5/5
(Rats orally).....25 mg./kg. 5/5/5 (LD 95)

		Percent	Percent
insecticidal values.....	flies.....	0.1	100
	spider mites.....	0.01	100
	black bean aphids.....	0.0001	95
	mosquito larvae.....	0.001	100
	systemic action on black bean aphids.....	0.1	100

Toxicity.....100 mg./kg. 5/5/5 (LD 95)
(Rats orally)

		Percent	Percent
insecticidal values.....	flies.....	0.1	100
	black bean aphids.....	0.0001	80
	Colorado beetles.....	0.1	40
	spider mites.....	0.001	100
	mosquito larvae.....	0.001	100
	systemic action on black bean aphids.....	0.1	100

The following examples are given by way of illustration only and without restricting the present invention thereto:

Example 1

80 g. ammonium salt of O,O-dimethyl-thiol-phosphoric acid are dissolved in 70 ml. water. At 60° there are

added slowly 74 g. (2-chloro-2'-methyl-ethyl(1-)(ethyl-sulfide. The temperature of 60° is kept for one further hour. 250 ml. benzene are added and the benzene layer is separated, washed twice with water and then dried over sodium sulfate (anhydrous). The benzene is distilled off and the residue fractionated in vacuo. The main portion distills at 0.01 mm. Hg at 83°, the yield amounts to 96 g.

Example 2

190 g. ammonium salt of O,O-dipropyl-thiolphosphoric acid are dissolved in 300 ml. methanol. While stirring there are added slowly at 60° C. 148 g. (2-chloro-2'-methyl-ethyl(1-)(ethyl-sulfide. The temperature is kept at 60° C. for one further hour and then after cooling the reaction mixture is filtered with sulfur. The methanol is removed by distillation and the residue is taken up in 500 ml. benzene and washed thrice with 50 ml. water. The benzene layer then is dried over anhydrous sodium sulfate. After distilling off the benzene the residue may be purified by vacuum distillation. There are obtained 224 g. of the new ester of the above formula.

Example 3

190 g. of an ammonium salt of diethylthiol phosphoric acid are dissolved in 400 ml. of 98% alcohol, 140 g. of 2-chloro-2'-methylthioethyl ether are added at 55° C. The temperature is kept at 60° C. for one hour, the salts are filtered off with suction and the methyl alcohol is separated by distillation in vacuum. The residue is taken up in 500 ml. of ether, the ethereal solution is washed twice with 50 ml. of water, dried and distilled. 175 g. of the new ether of B.P. 0.01 mm./92° C. are obtained as colorless water-insoluble oil.

Example 4

17 g. of potassium hydroxide are dissolved in 50 ml. of water. 53 g. of dimethyl dithiophosphoric acid are added at 20° C. While stirring at 40° C., 43 g. of 2-chloro-2'-methylthioethyl ether are added in drops. The temperature is kept at 45° C. for 30 minutes, the solution is then cooled to room temperature and the reaction product is thoroughly shaken with 300 ml. of benzene. The benzene solution is washed twice with 100 ml. of water, separated and dried. After removing the benzene the new ester distills over under a pressure of 0.01 mm./90° C. 35 g. of the ester are obtained as colorless water-insoluble oil.

Example 5

17 g. of potassium hydroxide are dissolved in 50 ml. of water. 60 g. of diethyl dithiophosphoric acid are added at 20° C. While stirring at 45° C., 43 g. of 2-chloro-2'-methylthioethyl ether are added dropwise to the solution. The temperature is kept at 45° C. for one hour. The solution is then cooled to room temperature, 300 ml. of ether are added, the ethereal layer is separated, washed twice with 100 ml. each of water, dried and distilled. 49 g. of the new ester of the B.P. 0.01 mm./104° C. are obtained as water-insoluble colorless oil.

the sulfoxide ester are obtained as yellowish, water-soluble oil. Yield: 86.7% of the theoretical.

Example 12

37 g. (0.15 mol) of the sulfide groups-containing ester of the following composition

are added dropwise at 5-10° C. to a suspension of 33 g. (0.21 mol) of potassium permanganate and 32 g. (0.13 mol) of magnesium sulfate in 250 ml. of water and 50 ml. of acetone. The suspension is stirred at 10° C. for another 30 minutes. The precipitated manganese dioxide contains a small excess of potassium permanganate which can be detected by the spot method. Sulfurous acid is added until the solution is colorless. The solution is then saturated with sodium sulfate and the resulting sulfone ester taken up in methylene chloride by shaking. After distilling and drying, 36 g. of the sulfone are obtained as colorless oil which is miscible with water. The purity of the crude product is satisfactory so that distillation is not required, prior to use. Yield: 88% of the theoretical.

Example 13

16.2 g. (0.0595 mol) of the sulfide group-containing ester of the following composition

are added dropwise at 5-10° C. to a suspension or solution of 14.2 g. (0.0869 mol) of potassium permanganate and 12.7 g. (0.052 mol) of magnesium sulfate in 200 ml. of water and 30 ml. of acetone. After stirring for another 30 minutes, sulfurous acid is introduced until the solution becomes colorless. The ester form is separated by addition of sodium sulfate and taken up in methylene chloride. The methylene chloride layer is dried with sodium sulfate and the solvent removed by distillation in vacuum.

15.8 g. of the new sulfone are obtained as water-soluble, viscous oil. The yield is 92.1% of the theoretical.

Example 14

38 g. (0.137 mol) of the ester of the following composition

are added dropwise at 5-10° C. to a suspension of 35 g. of potassium permanganate and 33 g. of magnesium sulfate in 400 ml. of water. The suspension is stirred at 10° C. for another 30 minutes and sulfurous acid is then added until the suspension becomes colorless. The precipitated sulfone ester is taken up in methylene chloride and the procedure of the preceding examples is followed. After distilling of the solvent, 34.5 g. of the sulfone ester are obtained as pale yellow, viscous oil of limited water solubility. The yield is 80.9% of the theoretical.

Example 15

31 g. (0.1 mol) of the ester of the following composition

are added dropwise at 5-10° C. to a suspension of 27 g. of potassium permanganate and 22 g. of magnesium sulfate in 300 ml. of water. After stirring at 5-10° C. for 30 minutes, sulfurous acid is introduced until the manganese dioxide is discolored and the sulfone ester form is separated by addition of sodium sulfate. By repeatedly shaking with methylene chloride, the ester is extracted from the solution. After drying and distilling of the solvent, 21 g. of the new sulfone ester are obtained as a yellowish oil which dissolves in water only sparingly. The yield is 62.8% of the theoretical.

Example 16

39 g. of the sulfoxide group-containing ester of the following composition

are added dropwise at 5-10° C. to a suspension of 33 g. (0.21 mol) of potassium permanganate and 32 g. (0.13 mol) of magnesium sulfate in 250 ml. of water and 50 ml. of acetone. The suspension is stirred at 10° C. for another 1/2 hour. The manganese dioxide which precipitates contains still a small excess of potassium permanganate. Sulfurous acid is added to remove this until the solution is colorless. The solution is saturated with sodium sulfate and the resulting sulfone ester is extracted with methylene chloride. After distilling and drying, 33 g. of the sulfone are obtained as colorless oil which is miscible with water.

Example 17

17.5 g. of the sulfoxide group-containing ester of the following composition

are added dropwise at 5-10° C. to a suspension or solution of 14.2 g. potassium permanganate and 12.7 g. magnesium sulfate in 200 ml. of water and 30 ml. of acetone. Stirring is continued for another 30 minutes and then sulfurous acid is introduced until the solution becomes colorless. The ester is separated by the addition of sodium sulfate and then taken up in methylene chloride. The methylene chloride layer is dried with sodium sulfate and the solvent removed by distillation in vacuum. 16 g. of the new sulfone are obtained as water-soluble, viscous oil.

75

We claim:

1. A thiophosphoric acid ester of the formula

in which R and R² stands for lower alkyl radicals, R¹ stands for a member selected from the group consisting of lower alkyl and lower chloroalkyl, A stands for a lower alkylene chain of at least two carbon atoms, X stands for a member selected from the group consisting of oxygen and sulfur, and Y stands for a member selected from the group consisting of S, SO and SO₂.

2. A thiophosphoric acid ester of the formula

in which R, R¹ and R² stand for lower alkyl radicals, X stands for a member selected from the group consisting of oxygen and sulfur, and Y stands for a member selected from the group consisting of S, SO and SO₂.

3. A thiophosphoric acid ester of the formula

in which R, R¹ and R² stand for lower alkyl radicals.

4. A thiophosphoric acid ester of the formula

in which R, R¹ and R² stand for lower alkyl radicals, and X stands for a member selected from the group consisting of oxygen and sulfur.

5. A thiophosphoric acid ester of the formula

in which R, R¹ and R² stand for lower alkyl radicals.

6. A thiophosphoric acid ester of the formula

in which R, R¹ and R² stand for lower alkyl radicals.

7. A thiophosphoric acid ester of the formula

in which R, R¹ and R² stand for lower alkyl radicals, and X stands for a member selected from the group consisting of oxygen and sulfur.

8. A thiophosphoric acid ester of the formula

9. A thiophosphoric acid ester of the formula

10. A thiophosphoric acid ester of the formula

11. A thiophosphoric acid ester of the formula

12. A thiophosphoric acid ester of the formula
